UNITED STATES PATENT OFFICE.

PETER M. ROSS, OF GRANTON, WISCONSIN.

DRINKING-CUP FOR CATTLE-WATERING SYSTEMS.

1,191,829.

Specification of Letters Patent.

Patented July 18, 1916.

Application filed November 9, 1914. Serial No. 871,084.

To all whom it may concern:

Be it known that I, PETER M. ROSS, a citizen of the United States, residing at Granton, in the county of Clark and State of Wisconsin, have invented certain new and useful Improvements in Drinking-Cups for Cattle-Watering Systems; and I do hereby declare the following to be a full, clear, and exact description of the invention, such as will enable others skilled in the art to which it appertains to make and use the same.

This invention comprehends certain new and useful improvements in drinking cups included in cattle watering systems and has for its primary object to provide a cup of this character which will be strong and durable as well as highly efficient in use and of simple construction and to which the water from the main supply pipe will be fed, in such manner that the sediment and the like within the cup is prevented from entering the water supply pipe.

The invention has for another object to provide a cup of this character which will be of such construction that a branch feed pipe connected therewith will be connected adjacent the upper edge of the cup and direct water into a downwardly directed spout secured to the inner face of the cup at one side or end thereof, and an air opening is provided above the upper end of the branch feed pipe to prevent the water from being drawn out of or sucked from out of the cups to the main supply pipe as the water in the other cup or cups in the system is used. A screen is secured to the lower end of the spout to prevent dirt and floating articles as well as the sediment in the cup from traveling upwardly into the spout to the branch feed pipe.

The invention has for a further object to generally improve and simplify the construction and operation of devices of this character and increases the efficiency thereof without materially increasing the cost of the same.

With these and other objects in view as will become more apparent as the description proceeds, the invention consists in certain novel features of construction, combination and arrangement of parts as will be hereinafter more fully described and claimed.

For a complete understanding of my in-

vention, reference is to be had to the following description and accompanying drawings, in which—

Figure 1 is a longitudinal section through a series of cups constructed in accordance with my invention and incorporated in a watering system for cattle and the like, said view also showing a section of the supply tank, Fig. 2 is a perspective view of one of the cups, Fig. 3 is a view similar to Fig. 2, partly in section, Fig. 4 is a top plan view of one of the cups and the branch feed pipe for the same and a section of the main feed pipe to which said branch feed pipe is connected, Fig. 5 is a detail sectional view on the plane of line 5—5 of Fig. 4, Fig. 6 is a detail view of the spout removed, and Fig. 7 is a perspective view of the blank from which the cup is formed.

Referring in detail to the drawings by numerals, 1 designates the supply tank to which water is fed by a pipe 2 leading from a main or other source of water supply having a float valve 3 on its end projecting into the supply tank 1, whereby the supply of water to said tank 1 may be readily controlled and automatically cut off as the system is filled.

Secured in the bottom of the supply tank 1 is one end of the main feed pipe 4, from which extend upwardly a plurality of branch feed pipes 5, each having its upper end 6 turned inwardly and secured in one side or end of one of the drinking cups 7 adjacent the upper edge thereof to feed water from the main feed pipe 4 to said cup 7, by way of the downwardly extending spout 8 secured to the inner face of the cup 7 opposite the branch feed pipe 5, as clearly shown in the drawings.

The downwardly directed spout 8 has its upper end 9 closed and a screen 10 secured in its lower end, and said spout 8 is preferably of triangular or V-shaped form in cross section. In the wall of the cup 7 opposite the upper end of the spout 8 and above the upper end 6 of the branch feed pipe 5, is provided an air inlet opening 11, through which air may enter the upper end of the spout 8 and thereby prevent the water from the cup 7 from being drawn back or sucked through the branch feed pipe 5 to the main feed pipe 4 after the level of the water in the cup 7 and spout 8 has fallen below the upper end 6 of said branch feed pipe 5. This will

prevent the water from being drawn out of the cup 7 as the water is used from the other cup or cups included in the system and connected with the main feed pipe 4.

5 In order to provide a cup 7 which will be strong and durable as well as highly efficient in use, I have formed the same of a single blank, of suitable material such as sheet metal and illustrated in Fig. 7, the body of
10 the blank forming the bottom 12 of the cup 7, while the longitudinal side extensions of the blank are bent upwardly along the dotted lines 13 to form the sides 14 of the cup 7, and the extensions are bent upwardly
15 along the dotted lines 15 to form the ends 16 of the cup 7. The blank has V-shaped incisions made at the corners thereof to separate the end extensions or flanges and the side extensions and also form triangular
20 flaps 17 projecting from the ends of the end extensions of the blank and adapted to be bent along the dotted lines 18 to place said flaps 17 against the outer faces of the sides 14 of the cup after said sides have been bent
25 upwardly, the upper corners of said flaps 17 overlapping and being secured in position by the upper edges 19 of the sides 14 which are bent outwardly and downwardly along the dotted line 20, over the upper edges of the
30 flaps 17. It will be understood that, if desired, the edges of the flaps 17 may be soldered or otherwise secured to the outer faces of the sides 14 and solder or the like may be employed in the corners of the cup
35 7 at the connection of the vertical edges of the sides 14 with the ends 16 to form a watertight connection between these parts and strengthen the cup 7.

40 The bottom 12 is provided, principally in its center, with a drain opening 21 within which may be secured a drain plug 22,

Copies of this patent may be obtained for five cents each, by addressing the "Commissioner of Patents.
Washington, D. C."

whereby the cup may be readily drained when desired.

While I have shown and described the preferred embodiment of my invention, it 45 will be understood that minor changes in the details of construction, combination and arrangement of parts may be made without departing from the spirit and scope of the invention as claimed or sacrificing any of 50 the advantages thereof.

What is claimed is:—

A watering system of the class described comprising a supply tank, a main feed pipe connected to the bottom of said tank extending 55 outwardly therefrom, a plurality of vertical branch feed pipes connected to and communicating with said main feed pipe at spaced distance apart, and a series of water cups each provided in one of their side or 60 end walls adjacent the upper edge with an air opening and an inlet opening, said air opening positioned above the inlet opening, the upper ends of said branch feed pipes being secured in said inlet openings of the 65 cups, and triangular shaped spouts secured over the openings of said cup on the interior thereof, said spouts extending downwardly 70 into said cup to a point just above the bottom thereof, and a screen secured over the lower open end of said spouts, said screen preventing dirt or floating particles of sediment from passing up through said spout and out into the branch feed pipe, the bottom of said cup provided with a central 75 opening and means for closing the opening.

In testimony whereof I affix my signature in presence of two witnesses.

PETER M. ROSS.
